CLAIM

The ornamental design for a temperature sensor, as shown and described.

DESCRIPTION

FIG. 1 is a front, right, and top perspective view of a temperature sensor showing the new design;

FIG. 2 is a back, left, and bottom perspective view thereof;

FIG. 3 is a right side view thereof;

FIG. 4 is a left side view thereof;

FIG. 5 is a front elevational view thereof;

FIG. 6 is a rear elevational view thereof;

FIG. 7 is a top plan view thereof;

FIG. 8 is a bottom plan view thereof;

FIG. 9 is a front, right, and bottom perspective view thereof of the temperature sensor coupled via a cable to a temperature sensor connector; and,

FIG. 10 is a top plan view coupled thereof of the temperature sensor coupled via a cable to a temperature sensor connector. The broken lines in the figures are shown for the purpose of illustrating portions of the temperature sensor and/or environmental matter that form no part of the claimed design.
